JOGGLE WEDGE

John Raymond Haughton, Carolina Beach, N. C.

Application October 20, 1942, Serial No. 462,768

6 Claims. (Cl. 61—66)

This invention relates to a joggle wedge which may be employed wherever it is desired to hold an object against movement by a wedging action and is especially adapted for use on marine ways when constructing ships and the launching thereof.

The primary object of the invention is the provision of a device of the above stated character, which may be easily and quickly installed and released from the holding position without mutilation or damage occurring thereto, and which will require less man-power in the launching of ships if employed for this purpose and a device which may be used as many times as desired.

With these and other objects in view as will become more apparent as the description proceeds, the invention consists of certain novel features of construction, combination and arrangement of parts as will be hereinafter more fully described and claimed.

For a complete understanding of my invention, reference is to be had to the following description and accompanying drawings, in which—

Figure 1 is a front elevation partly in section, illustrating a joggle wedge constructed in accordance with my invention and showing the same in a holding position.

Fig. 2 is a fragmentary side elevation, illustrating a flexible bail for releasably securing one of the side members of the wedge in holding position.

Fig. 3 is a sectional view taken on the line 3—3 of Fig. 1.

Fig. 4 is a perspective view illustrating one of the members of a coupling.

Fig. 5 is a diagrammatical view showing the present invention in use on a marine way.

Referring in detail to the drawings, the numeral 5 indicates the substantially rectangular frame including side members 6 and 7 and end members 8 and 9. The side member 6 and end member 8 are of integral construction with said members arranged at right angles to each other. The end member 8 has formed in one face thereof a notch 9' to be engaged by the beveled end 10 of the side member 7. Pivoted on the side member 7 is a flexible bail 11' which when brought into engagement with the end member 8 will sustain the beveled end 10 of the side member 7 in the notch 9'. It will be noted that the notch 9' is located a limited distance from the free end of the end member 8 so that the free end of the member 8 will act as a stop for limiting the sliding movement of the frame between objects A and B. The object A is fixed while the object B

is movable longitudinally of the object A. The frame is positioned as shown in Fig. 1 between the objects A and B with the free end of the end member 8 resting on the object A. With the frame between the objects A and B, a wedging action will be established to prevent movement of the object B relative to the object A.

The end member 9 is composed of sections 11 and 12 connected to each other by a hinge 13 the pintle of which is indicated by the character 14. The section 12 is connected to the side member 7 by a hinge 15 and a hinge 16 connects the section 11 to the side member 6. The hinge 13 permits the sections 11 and 12 to swing relative to each other and the hinges 15 and 16 permit said sections to swing upon the side members 6 and 7. When the sections 11 and 12 are moved to assume a position angularly to each other this brings about a movement of the side member 7 toward the side member 6, the frame then becomes collapsed.

A member 17 is apertured to receive the pintle 14 of the hinge 13 and has formed thereon a ball 18 received within a socket-type coupling 19. A feed stem 20 is threaded in the end member 8 and one end thereof is equipped with a ball 21 received in the coupling 19. The coupling 19 is of sectional formation to permit the balls of the stem and member 17 to be assembled therein. A rivet 22 joins the sections of the coupling 19 together. The feed stem 20 may rotate relative to the member 17 and the latter may have pivotal movement with respect to the feed stem due to the arrangement of the coupling 19.

The feed stem 20 has a handle 23 connected thereto by a universal joint 24 which will permit positioning of the handle at different angles to the feed stem so that the latter may be rotated conveniently when the device is in use.

When it is desired to release the object B from the object A, the feed stem 20 is rotated by the handle 23 causing the sections 11 and 12 of the end member 9 to move into angular position drawing the side member 7 toward the side member 6. Said side member 7 pivots in the notch 9' and the bail pivots on the end member 8 as well as on the member 7 or if desired, the bail may be moved off of the end member 8 prior to rotating the stem. Therefore, it will be seen that the frame 5 can be easily collapsed which will free the object B from the object A.

Referring to the use of the present invention to a marine way as shown in Fig. 5, a number of joggle wedges are employed between the slide-ways 25 and the groundways 26 to prevent the

slideways from moving or sliding on the groundways during the construction of a ship on the marine way. The ship under construction is designated by the character 27 and arranged between the bottom thereof and the slideways are packing blocks 28 and wedges 29 which are driven in between the packing blocks and the slideways for the purpose of levelling the ship on the marine way. It will be seen that the groundways are arranged at opposite sides of the keel of the ship and extend longitudinally of the latter and the top faces slope towards each other and the outer edges are provided with upstanding flanges 30 extending substantially the full length of the groundways. The joggle wedges constructed in accordance with the present invention are arranged between the flanges 30 and the outer longitudinal edges of the slideways and establish wedging action therebetween so that the slideways will not move over the groundways longitudinally of the latter. To prevent the slideways from moving towards each other and after joggle wedges have been arranged in position, said slideways are jacked away from each other and held in said position by spreaders (not shown) arranged between the slideways which place pressure on the joggle wedges. After the ship has been constructed and is ready for launching, the joggle wedges must be removed and due to the present construction of the joggle wedges, it is a simple matter for a person to easily and quickly collapse the joggle wedges by rotating the handles 23 thereof freeing the slideways from the groundways so that when the usual trigger mechanism of the marine way is operated, the slideways may then slide freely over the groundways to bring about launching of the ship, in the water.

Therefore, it will be seen that the releasing of the joggle wedges can be carried out rapidly and with no danger of damage or mutilation thereto so that the joggle wedges can be used as many times as desired.

While I have shown and described the preferred embodiment of my invention, it is to be understood that minor changes in construction, combination, and arrangement of parts may be made without departing from the spirit and scope of the invention as claimed.

Having thus described my invention, what I claim is:

1. In combination with a marine way including groundways having upstanding flange portions, slideable supporting slideways, joggle wedges arranged between the flange portions and the slideways and each including a collapsible wedge frame and manually operated means for collapsing the frame.

2. A joggle wedge, a wedging frame including opposed portions, means hingedly connecting said portions, means opposed to said hinged means connecting said portions to sustain the frame in wedging position, and means for releasing one of said portions for movement toward the other portion for collapsing the frame.

3. In a joggle wedge, a wedging frame including side members, means connecting said members whereby one of the members may move toward the other member, a sectional end member hinged to the side members with the sections hinged to each other, and an operating means connected to the sections of said end member, whereby the sections may be moved into angular relation to each other for moving one of the side members toward the other side member.

4. In a joggle wedge, a wedging frame including side members and end members, one of said end members formed integrally with one of the side members and notched to receive the other side member, a bail pivoted to the latter-named side member and engageable with the latter-named end member, the other end member including hingedly connected sections, hinges connecting the sections to the side members, and an operating means connected to the sections for the movement thereof relative to each other and relative to the side members.

5. In a joggle wedge, a wedging frame including side members and end members, one of said end members formed integrally with one of the side members and notched to receive the other side member, a bail pivoted to the latter-named side member and engageable with the latter-named end member, the other end member including hingedly connected sections, hinges connecting the sections to the side members, a coupling connected to the sections of the sectional end member, and a feed stem threaded into the other end member and connected to said coupling.

6. In a joggle wedge, a wedging frame including side members and end members, one of said end members formed integrally with one of the side members and notched to receive the other side member, a bail pivoted to the latter-named side member and engageable with the latter-named end member, the other end member including hingedly connected sections, hinges connecting the sections to the side members, a coupling connected to the sections of the sectional end member, a feed stem threaded into the other end member and connected to said coupling, a handle, and a universal joint connecting the handle to the feed stem.

JOHN RAYMOND HAUGHTON.
